UNITED STATES PATENT OFFICE.

WILLIAM A. BOYDEN, OF BROCKTON, MASSACHUSETTS, ASSIGNOR TO UNITED SHOE MACHINERY COMPANY, OF PATERSON, NEW JERSEY, A CORPORATION OF NEW JERSEY.

APPARATUS FOR USE IN THE MANUFACTURE OF BOOTS AND SHOES.

Specification of Letters Patent.

Patented Apr. 28, 1914.

1,094,547.

Application filed June 21, 1911. Serial No. 634,503.

To all whom it may concern:

Be it known that I, WILLIAM A. BOYDEN, a citizen of the United States, residing at Brockton, in the county of Plymouth and State of Massachusetts, have invented certain Improvements in Apparatus for Use in the Manufacture of Boots and Shoes, of which the following description, in connection with the accompanying drawings, is a specification, like reference characters on the drawings indicating like parts in the several figures.

This invention relates to apparatus for use in the manufacture of boots and shoes. The lasting operations on the toe portions of shoes result in damaging a very substantial percentage of the shoes by causing the leather to crack or break where it is pulled tightly over the toe of the last. This effect is particularly troublesome where lasts having high toes are used. It has been found that the damage produced in this manner can be very materially reduced and that the lasting of the toe portion of the shoe can be facilitated by subjecting this part of the shoe to the action of hot steam or vapor prior to the lasting operation. One of the difficulties encountered in treating shoes in this manner, however, is that of burning or shriveling up the upper leather caused by subjecting it to too high a temperature.

It is a particular object of the present invention to devise an apparatus for treating portions of shoes by steam or vapor in the manner above indicated in which the temperature of the vapor can be readily controlled and in which the danger of burning the shoe shall be substantially eliminated.

One embodiment of the invention is shown in the figure of the accompanying drawing.

The apparatus shown comprises a tank 2 which may conveniently be made of wood and lined with sheet metal as indicated at 4. A steam pipe 6 is led into the tank and is joined to a perforated pipe section 8 lying along the bottom of the tank. The pipe 6 is connected through a suitable valve 10 with a steam supply. In order to carry away the condensed steam, a drip or discharge pipe 12 is led into the tank and has its intake end positioned in the tank above the level of the perforated section 8. It will be evident, therefore, that the tank will always be filled

with water up to the level of the intake end of the discharge pipe 12, thereby maintaining the section 8 of the steam pipe always submerged. I prefer this arrangement for the reason that it affords a comparatively large body of steam or hot vapor to act upon the shoe and particularly because this arrangement enables the workman to regulate the temperature of the vapor easily by manipulating the valve 10. Furthermore, the body of water cools off the steam to such a degree that the danger of burning the shoe, which otherwise would be considerable due to variations in steam pressure, is practically eliminated. It should be noted that the steam pipe 6 enters the tank above the water line and thus avoids the necessity of providing a tight joint at this point.

The front wall of the tank 2 is provided with two apertures 14 preferably shaped to accommodate the toe of a shoe when supported sole upward. The end sections of the tank 2 are extended and hold between them a shoe rest which may consist of a board 16 notched at 18 to engage the upper of the shoe and support it in inverted position with its toe in the tank. The metal lining of the tank is cut away at the holes 14 to such an extent that the wood of the tank protects the shoe from contact with the metal which might burn or discolor the shoe.

In using the apparatus, the workman usually lasts the sides and heel of a pulled over shoe and then supports it in the rest 16 with its toe projecting into the tank where it will be subjected to the action of the vapors rising from the body of water. The workman next lasts the sides and heel of another shoe and places it in the rest 16 with its toe in position to be steamed. Usually the first shoe has become sufficiently softened by this time to last easily and the workman therefore removes it and lasts the toe while the leather is still hot and moist. I have found that the treatment of the stock in this manner makes the lasting of the toe very much easier, thus enabling the workman to last more shoes in a given time; that it avoids most of the damage that heretofore has been experienced in lasting toes and that the toe dries out in a better condition than when treated in accordance with the methods heretofore practised.

The temperature at which the vapor should be maintained will vary somewhat with the character of the stock under treatment, but for most leathers satisfactory results can be obtained by so regulating the temperature that the workman can just touch his fingers in the water quickly without being scalded.

In treating the better grades of shoes, I prefer to use the apparatus with the steam inlet pipe submerged to a considerable depth since the steam then rises from the water in a very saturated condition and thoroughly penetrates the parts of the upper stock that must be disposed about the toe of the shoe; but for the cheaper grades of work where the shoes must be kept moving as rapidly as possible I prefer to use drier steam which penetrates the leather more quickly without moistening the toe stiffener and lining as much as does the more saturated vapor. For the latter grades of work, therefore, I lower the end of the drip pipe to a point that will keep the water just above the level of the perforation at the bottom of the steam pipe 8. The steam in entering the tank, therefore, passes through a very shallow depth of water and does not take up as much moisture as it would otherwise. I find that shoes treated in the apparatus, when so adjusted, dry very quickly and are therefore ready for the subsequent operations with but little delay.

It will be obvious that shoes can be treated in this manner to advantage before they are pulled over.

Having fully described my invention, what

I claim as new and desire to secure by Letters Patent of the United States is:—

1. An apparatus of the character described, comprising a tank, said tank having one or more apertures for the reception of the toe of a shoe, a steam inlet pipe positioned in said tank, and a discharge pipe having its intake end positioned in the tank above the level of the steam pipe.

2. An apparatus of the character described, comprising a tank having a plurality of apertures each shaped for the reception of the toe of a shoe, a perforated steam inlet pipe positioned in said tank, a discharge pipe having its intake end positioned in the tank above the level of the steam pipe, and a rest for supporting a shoe with its toe in one of said apertures.

3. An apparatus of the character described, comprising a tank for a body of water, a steam inlet pipe arranged to deliver steam into said body of water, a discharge pipe having its intake end opening into said tank at a point above the level at which the steam is discharged, and a shoe support positioned adjacent to said tank, said tank being constructed to direct the vapor rising from said body of water against a portion only of the shoe sustained by said support.

In testimony whereof I have signed my name to this specification in the presence of two subscribing witnesses.

WILLIAM A. BOYDEN.
